(57) **CLAIM**

The ornamental design for a pull handle for a rolling case, as shown and described.

DESCRIPTION

FIG. 1 is a front perspective view of the pull handle for a rolling case;

FIG. 2 is a rear perspective view of the same;

FIG. 3 is a front elevational view of the same;

FIG. 4 is a left side view of the same, the right side view being a mirror image thereof;

FIG. 5 is a rear elevational view of the same;

FIG. 6 is a top plan view of the same;

FIG. 7 is a bottom plan view of the same;

FIG. 8 is a perspective view of the pull handle for a rolling case of FIG. 1, shown in a collapsed configuration;

FIG. 9 is a front elevational view of the pull handle for a rolling case of FIG. 1, shown in a collapsed configuration;

FIG. 10 is a left side view of the pull handle for a rolling case of FIG. 1 shown in a collapsed configuration, the right side view being a mirror image thereof;

FIG. 11 is a rear elevational view of the pull handle for a rolling case of FIG. 1, shown in a collapsed configuration;

FIG. 12 is a front elevational view of the pull handle for a rolling case of FIG. 1, shown in a collapsed configuration; and,

FIG. 13 is a rear elevational view of the pull handle for a rolling case of FIG. 1, shown in the collapsed configuration of FIG. 12.

(Continued)

The broken lines in the drawings illustrate environment and form no part of the claimed design.
